CLAIM

The ornamental design for a sterilizer box for braces, substantially as shown and described.

DESCRIPTION

FIG. 1 is a top, front and left side perspective view of a sterilizer box for braces, showing my new design;

FIG. 2 is a bottom, rear and right side perspective view;

FIG. 3 is a top, front, left perspective view, shown opened in an alternative configuration for clarity of disclosure;

FIG. 4 is a top plan view of the sterilizer box for braces of

FIG. 1;

FIG. 5 is a bottom plan view thereof;

FIG. 6 is a left side elevational view thereof;

FIG. 7 is a right side elevational view thereof;

FIG. 8 is a rear elevational view thereof; and,

FIG. 9 is a front elevational view thereof.

The broken lines in the drawings illustrate the portions of the sterilizer box for braces, which form no part of the claimed design.

1 Claim, 9 Drawing Sheets
